UNITED STATES PATENT OFFICE.

HENRY GALLAGER, OF SAVANNAH, GEORGIA.

CAR-BRAKE.

SPECIFICATION forming part of Letters Patent No. 238,379, dated March 1, 1881.

Application filed January 12, 1881. (No model.)

To all whom it may concern:

Be it known that I, HENRY GALLAGER, of 5
Savannah, in the county of Chatham and State
of Georgia, have invented a new and Im-
proved Car-Brake; and I do hereby declare
that the following is a full, clear, and exact
description of the same, reference being had
to the accompanying drawings, forming part
of this specification, in which—

10 Figure 1 is a plan view with one end of the
floor-timbers and the upper cross-bar of the
truck broken away. Fig. 2 is a section through
the line *x x*, Fig. 1. Fig. 3 is a section through
the line *y y*, Fig. 1. Fig. 4 is a plan view of
15 a modification. Fig. 5 is a sectional detail re-
lating thereto.

My invention relates to certain improve-
ments in car-brakes of that type which auto-
matically apply the brakes through the move-
20 ment of the draw-bar.

My improvements contemplate the constant
pressure of the brakes upon the wheels when-
ever the draw-bar is in its normal position of
rest, and which brakes are released or with-
25 drawn from the wheels whenever the draft-
strain pulls the draw-bar out, or whenever the
draw-bars are driven in by backing, so that
whenever the locomotive approaches a condi-
tion of rest, whether in moving forward or
30 backward, the brakes commence to be applied
automatically, but are not applied when the
power of the locomotive is being transmitted
to the cars for the transportation of the same.

My invention consists in the peculiar means
35 for accomplishing these results in a practical
way, which means are applicable alike to either
steam or street cars, as will be hereinafter
more fully described.

In the drawings, A represents the floor-tim-
bers of a car, beneath which, at each end, are
40 arranged the trucks, as usual. Each truck
being exactly alike, a description of one will
suffice for both. The side frames of each
truck, which carry the bearings of the wheels,
45 are connected by two cross-bars, B B', whose
ends are separated by blocks *a a'*, Fig. 2, so as
to hold these cross-bars vertically one above
the other, with a space between them, in which
50 space are located the devices for applying the
brakes. Longitudinally in this space and
crosswise of the car is arranged a deflector-

lever, C, whose ends are connected, by rods *b b*,
to the ends of a corresponding lever on the
other truck similarly equipped. This deflector-
lever is fulcrumed on a vertical bolt in the 55
middle of the cross-bars, and has upon its
under side an elongated lug, *c*, extending on
both sides of its fulcrum. Within the space
between the two bars B B', and bearing
60 flatly against the opposite sides of the elon-
gated lug, are two bar-springs, D D', stiffly con-
nected at their outer ends to one of the bars
B B'. The inner ends of these stiff springs
are jointed to the rods *d d'*, which extend lon-
gitudinally with the car to the two brake-bars 65
E E' of each truck. Now, whenever the de-
flector-lever C rests at right angles to the lon-
gitudinal axis of the car the ends of the
springs D D' approach each other as closely
70 as the flat sides of the lug *c* will permit, and
these springs consequently draw the rods *d d'*
to the center and apply the brake-bars to the
wheels. When, however, the deflector-lever
C is thrown into an oblique position, the ends
75 of the springs D D' are forced apart by the
lug *c*, and the brake-bars E E' with their shoes
are thrown away from the wheels. As shown,
these brake-bars have their shoes jointed at
the top to the ends of longitudinal bars F F,
80 resting above the end frames of the trucks,
just outside of the wheels; but they may be
supported by chains, or in any other suitable
way.

For causing the deflector-lever C to control
the brakes automatically through the draw- 85
bar, I attach to the draw-bar G a link-rod, *e*,
connecting with a lever, H, resting in the space
between cross-bars B B', just above the de-
flector-lever. The outer end of this lever H is
90 fulcrumed to the outer ends of these cross-
bars. At its middle it is jointed to the end of
the deflector-lever C, and at its other end,
where it connects with the draw-bar, it is pro-
vided with a curved slot, *b*, through which
95 passes the fulcrum-bolt of the deflector-lever
to limit the movement of this lever H. Now,
it will be seen that in the normal position of
rest of the draw-bar the brakes are applied by
the springs D D'. When, however, a draft is
100 applied to start the car, the draw-bar pulls
against the tension of the springs, through the
levers H and C, and the brake-bars are pro-

jected away from the wheels, remaining so until the draft is relieved. On the other hand, when the draw-bar is driven in by the backing of the cars, the lever C is deflected in the opposite direction, and the brakes released from the wheels and held apart from the same so long as the compressing strain exists. With this construction it will be seen that the same mechanism supplies means for automatically applying and removing the brake, no matter whether going backward or forward, and, besides, the spring serves the additional function of rendering the draw-bars yielding.

In modifying my invention for use on street-cars, I locate (see Fig. 4) the springs D² D³ on a cross-bar, I, on the bottom of the car-frame, between the wheels, and arrange the same deflector-lever C' upon a center bolt with its lug depending between the lapping inner ends of the springs, and the ends of the lever C' I connect to the independent levers G', corresponding to H in Fig. 1, and which levers are connected, by chains, to the draw-bars H', the ends of these springs being connected, by rods d' d', to the brake-bars E² E³. The action of these devices is substantially the same as that before described, except that no provision is made for backing, none being required. To put the brakes, however, in this case under the control of the driver, so as to permit him

to hold them away from the wheels without regard to the draft, as in going down grade, I perforate the draw-bar at g, and provide beneath the platform a compressible spring, h, Fig. 5, bearing a locking-stud, i, that passes through the holes on the draw-bar to hold it in any given position, this stud being removed from the holes at the will of the driver by a stud, j, rising through the platform, which may be depressed by the driver's foot.

40

Having thus described my invention, what I claim as new is—

1. The deflector-lever C, fulcrumed in its middle transversely to the car, and provided with lug c, combined with the springs D D', bearing on opposite sides of this lug a set of rods connecting with the brake-bars, and a lever connecting with the draw-bars, substantially as and for the purpose described.

2. The draw-bar of a street-car, perforated and combined with a spring bearing a locking-stud, i, and a compressible stem, j, and with a set of brakes arranged, as described, to be applied when the draw-bar is in the normal position of rest.

HENRY GALLAGER.
